Primary Examiner — Cynthia Ramirez*Assistant Examiner* — Gino Colan(74) *Attorney, Agent, or Firm* — Venable LLP; Steven J. Schwarz(57) **CLAIM**

The ornamental design for spacecraft system, as shown and described.

DESCRIPTION

FIG. 1 is a perspective view of a spacecraft system according to an embodiment of the claimed design;

FIG. 2 is a front elevational view of the spacecraft system of FIG. 1;

FIG. 3 is a rear view elevational view of the spacecraft system of FIG. 1;

FIG. 4 is a left elevational view of the spacecraft system of FIG. 1;

FIG. 5 is a right elevational view of the spacecraft system of FIG. 1;

FIG. 6 is a top elevational view of the spacecraft system of FIG. 1;

FIG. 7 is a bottom elevational view of the spacecraft system of FIG. 1; and,

FIG. 8 is a perspective view of the spacecraft system of FIG. 1, shown docked to a canisterized satellite dispenser.

The features shown in broken lines are environment only and not part of the claimed design.
